LIQUID METER

Frank Horton, London, England, assignor to
Foreign Rights (Precision Meters) Limited,
London, England

Application July 26, 1938, Serial No. 221,429
In Great Britain August 12, 1937

6 Claims. (Cl. 73—253)

This invention relates to liquid meters of the displacement or positive or semi-positive type and has for its object to provide an improved form of meter which is of simple construction and in which the parts may be readily and accurately manufactured and wherein the calibration of the device may be effected in a simple manner.

The invention consists in a liquid meter comprising rotor or piston elements (preferably a pair), each rotatable in a cylinder and having a radial vane extending to the cylinder wall, oscillatable partition means engaging each piston and adapted to separate the pressure and discharge side of the cylinder, the vane on one piston being relatively displaced to that on the other.

The invention also consists in a liquid meter comprising rotor or piston elements (preferably a pair) each rotatable in a cylinder and having a radial vane extending to the wall of the cylinder, a pressure port opening into a pressure chamber communicating with the cylinder, and a discharge port opening into the cylinder, oscillatable partition means engaging the piston and separating the pressure and discharge side of the cylinder, the vane on one piston being relatively displaced to that on the other piston.

Further features of the invention will be hereinafter described and defined in the claims.

In the accompanying drawings:

Figure 1 is a longitudinal section of a liquid meter according to the invention.

Figure 2 is a cross section,

Figure 3 is a cross section of the inner block showing the inlet and discharge ports and chambers;

Figure 4 is a longitudinal section of a calibrating and temperature controlling device.

In carrying the invention into effect according to one convenient mode, a central block 10 is provided to the opposite faces of which a pair of cylinder units 11 and 12 are secured. The central block 10 is provided with inlet and discharge chambers 13 and 14 respectively, having pipe connections 15 and 16. The inlet chamber 13 opens into side ports 17 and 18 while the discharge chamber is provided with side ports 19 and 20. The ports are arranged at appropriate positions in side walls 21 of the central block.

The cylinder units are provided with chambers 22, 23 of circular cross section which at one side open into crescent or other suitably shaped chambers 24, 25 which accommodate oscillating partitions 26, 27. The inlet ports 17 and 18 open into the chambers 24 and 25 respectively while

the discharge ports 19 and 20 open respectively into the cylinders 22 and 23. End closing cover plates 32 and 33 close the cylinders and form walls thereof.

5 The partitions 26 and 27 are freely mounted to oscillate upon a spindle 28 which extends through an aperture 29 in the central block.

Each partition is formed as a plate having end flanges 30 and is provided with a nose portion 31 adapted to engage the surface of the piston.

The partitions and nosepieces extend completely across the cylinders to engage the walls of the cylinders formed by the walls 21 and end closing cover plates 32, 33.

10 The partitions are each provided with a boss 34 engaging the wall of a recess 35 opening into the valve chamber.

The cylinders are provided with rotors or rotary pistons which are secured to a common spindle 36 extending through an opening 38 in the central portion of the block and mounted in bearings 37. Each piston is formed in two parts 39 and 40, the part 39 having a sleeve 39a by which the piston is keyed to the spindle 36. The other part 40 is mounted upon the sleeve 39a and is capable of rotary movement relatively thereto, a nut 41 on the screwed end of the sleeve 39a locking the parts together.

15 The cross section of the piston is circular and mounted on the outside of each part of the piston is one of a pair of projections or cams 42 forming a radial vane. Each cam extends the full width of the cylinder. The piston is arranged concentrically within the cylinder and the cam 42 extends radially to the wall of the cylinder. These vane projections or cams 42 are formed with a surface conforming to the curved surface of the piston and are bolted thereto by bolts 43 extending through holes in the piston wall, suitably shaped washer elements 44 being provided within the piston for the heads of the nuts to seat on. The arrangement is such that the projections or cams 42 may be spaced apart so that the effective capacity of the cylinder may be adjusted whereby the meter may be calibrated. In view of the relatively simple construction of the cylinder and piston it is anticipated that the necessary adjustment for calibration will be of a small order.

20 The adjustment of the cam projections relatively to one another is effected by an eccentric 45 mounted upon the part 39 of the piston and seating within an aperture 46 in the other part. On rotating the eccentric 45, first slackening back the nut 41, relative rotational movement is imparted to the piston parts with consequent spac-

ing of the cam parts or moving them together. After adjustment the nut 41 is tightened and also the nut on the eccentric member.

The circumferential extent of the vane 42, 42 is such that when the piston moves to a position 180° from that shown in Figure 3 the vane extends across the opening between the cylinder and the valve chamber so that pressure from the inlet port 17 is cut off from the cylinder.

As the piston rotates under the pressure of the liquid from the inlet port 17 acting against the vane, liquid on the discharge side will flow out of the port 19. Under these conditions the partition 26 will be subject to a higher pressure on the inlet port side, thus holding it in contact with the piston 15 and dividing the cylinder space.

When dealing with low pressures it may be that the difference in pressure, or the position of the meter, is such that the partition will not remain in contact with the piston and to counteract such conditions the partition is provided with a relatively light spring 146 (Figure 2) which holds it in the desired position. The spring is connected to an adjustable pin 47 whereby its tension may be adjusted.

The pistons are arranged on the spindle 36 so that the vanes 42 of one piston are displaced 180° relatively to those of the other piston so that when the vanes of one piston are in the position to cut off the pressure chamber from its cylinder, 30 the vane of the other piston will be under fluid pressure so that the first-mentioned piston will be driven over the dead spot.

The end cover plates 32, 33 which form the walls of the cylinders and pressure chambers are 35 provided with apertures 48 which are closed by caps 49 which may be removed for calibration purposes.

In one cap 49 a spindle 50 is provided for an indicating and/or registering mechanism located 40 within a suitable casing 51, means being provided for coupling the spindle 50 to the spindle 36 of the pistons.

In operation, the parts being in the position indicated in Figure 2, liquid under pressure by a pump or otherwise passes through the inlet port 17 and enters the cylinder and exerts force on the radial vane 42 causing the piston to rotate and force liquid on the other side of the vane out through the discharge port 19. As the vane 50 approaches the discharge port it engages the partition and oscillates this over. When the piston vane occupies the dead spot the pressure is cut off from the cylinder, i. e. when the vane moves over the edge 66 of the pressure chamber. The movement of the vane continues past the dead spot owing to the other piston so that the vane will move past the partition allowing the pressure of the liquid together with the force of the spring of the partition to cause the partition 55 to follow the contour of the piston vane.

It will be appreciated that the disposition of the inlet and discharge ports and the dimensions of the partition and piston vanes are such that when the vane moves over the discharge port and actuates the partition there will be no through passage from the inlet to the discharge port.

The discharge ports are provided with a portion which extends into the partition chamber 70 and is never covered by the piston vanes whereby locking of liquid on the discharge side between the piston vanes and partition is avoided.

According to a modified form each piston may be constructed in one piece with a fixed dimen-

sion vane and calibration effected by other means.

Thus referring to Figure 4 a freely movable piston 52 is mounted in a cylinder 53, the end chambers 54 and 55 of which are coupled by the outlets 56, 57 to the meter cylinder chambers 22, 23 respectively.

At each end of the calibrating piston 52 a hollow nut 58 is provided which co-operates with an adjustable stop 59 screwed into the cylinder cap 60. By adjusting the stop or stops 59 the stroke of the piston 52 is altered, thereby adjusting the volume of the meter cylinder chambers 22, 23. By this means calibration of the meter may be made.

Conveniently the calibrating cylinder 53 and piston 52 may be utilised as a temperature adjustment device adapted automatically to vary the volume of the meter cylinder chambers 22, 23 in accordance with changes of temperature in the liquid being metered.

For this purpose the calibrating piston 52 is provided with two heads 52a, 52b adjustable towards one another. The piston heads are hollow and provided with cup members 160 connected together by a "siphon" bellows 61 and having aperture 62 so that the interior of the "siphon" bellows is in communication with the annular spaces between the cup 160 and the piston head.

The annular spaces within the piston heads and the interior of the "siphon" bellows are filled with a quantity of the same liquid as that which is being measured. The space 63 between the piston heads which extends between the "siphon" bellows and the cups 160 communicates by the outlet 64 with the inlet side of the central block 10 of the meter so that the actual liquid being measured has access to these spaces and thus the temperature of the liquid will be imparted to the sealed liquid within the "siphon" bellows and piston heads. On temperature variations occurring the bellows 61 will extend or contract and thus move the piston heads relatively to one another and vary the stroke of the piston, whereby the volume of the meter cylinder chambers 22, 23 is varied in accordance with temperature variation.

Should it be desired to meter hot liquids a second connection to the inlet side of the central block 10 is made by the aperture 65 in the cylinder 53 so that a circulation of the hot liquid is obtained. When metering normal temperature liquids the aperture 65 is closed by a plug.

The calibrating cylinder may be mounted on the meter casing in any convenient position.

The meter is adapted for operation under low pressure heads but may also be arranged for relatively high pressures by suitably designing the parts to withstand the pressures desired. It may be used for various kinds of liquid, such as lubricating oils, petrol, and consumable liquids such as milk. In the case of consumable liquids the parts could be made of material such as stainless steel and the end covers would be mounted so that they may be readily removed for cleaning purposes.

The improved meter has a large metering capacity for its size and operating under a low head is suitable for use on aeroplanes and also petrol and Diesel oil wagon delivery.

I claim:

1. A liquid meter comprising a pair of cylinders arranged side by side on a common axis, a piston element in each cylinder, said piston elements being coupled to a common shaft, each

of said piston elements having a radial part extending to the wall of the respective cylinder, said radial parts being diametrically opposed and having surfaces conforming to the curvature of the cylinder wall, offset chambers opening into said cylinders partition means mounted for oscillation in said chambers and projecting into the cylinders to contact with the corresponding piston element, inlet ports for liquid to be metered opening into said chambers, discharge ports opening into the cylinders, said partition means separating the inlet and discharge ports of the associated cylinder and being movable into said chambers while still permitting the passage of liquid into the cylinder, the arrangement being such that the flow of liquid into the cylinder is cut off once during each revolution of the piston elements by the radial part of the piston element covering the opening between the cylinder and its off set chamber.

2. A liquid meter comprising a pair of cylinders arranged side by side on a common axis, a piston element in each cylinder, said piston elements being coupled to a common shaft, each piston element comprising a main circular part arranged concentric with the cylinder and a radial part extending to the cylinder wall and having a surface conforming to the curvature of said wall, said radial part of one piston element being diametrically opposed to the radial part of the other piston element, oscillatable partition elements engaging each piston element, inlet and discharge ports opening into each cylinder on opposite sides of the respective partition element, the inlet and discharge port of

each cylinder being completely closed during each revolution of the respective piston element, the circumferential dimension of the radial extensions of the piston elements being adjustable to vary the effective volume of the cylinders for calibrating the meter.

5 3. A liquid meter as claimed in claim 2 wherein each of said radial parts of the piston elements is formed in two parts adjustable relatively to one another in a circumferential direction.

10 4. A liquid meter as claimed in claim 2 wherein each piston element is formed in two portions, and each radial part of the piston elements is formed in two parts, each of said portions of the piston elements carrying one of said parts of said radial part and means for rotating the portions of each piston element relatively to one another to adjust the circumferential dimension of the radial part.

15 5. A liquid meter as claimed in claim 2 wherein each piston element is formed in two portions and each radial part of the pistons is formed in two parts, each of said portions of the piston elements carrying one of said parts of said radial part, a rotatably mounted eccentric carried by one of said piston element portions and engaging a recess in the other of said piston portions of each piston element, and means for rotating said eccentrics to rotate said piston element portions relatively to one another.

20 6. A liquid meter as claimed in claim 1 wherein the discharge ports are arranged in the side walls of the cylinders and extend into said offset chambers for the purpose set forth.

35 FRANK HORTON.
